PHONOGRAPH

Sam G. Langley, Maplewood, N. J., assignor to
 Thomas A. Edison, Incorporated, West Orange,
 N. J., a corporation of New Jersey

Application October 1, 1937, Serial No. 166,768

16 Claims. (Cl. 274—17)

My invention relates to phonographs and more particularly to those of a business or commercial type. It is especially concerned with means for detachably coupling the sound transmitting tube and remote control devices to such machines.

In the phonograph there is provided a sound translating device which engages the surface of a rotating record and moves transversely of the direction of record rotation. The sound translating device is usually adjustable for either recording or reproducing purposes. In recording, it impresses or cuts on the record surface a progressive modulated groove having a depth or lateral deflection in accordance with received sound waves. In reproducing, it follows and engages such a modulated groove to create sound waves in accordance with the undulations of the groove. For conveying the sound waves to, or away from, the translating device there is customarily employed a sound transmitting tube having at its far end a hand-piece adapted to be held in the hand of the operator and usable as a mouthpiece in recording, or alternatively as an earpiece in reproducing.

There is also provided an operating mechanism which includes broadly the means for performing all the mechanical functions necessary to the use of the phonograph. This mechanism comprises principally the means for effecting and controlling the rotation of the record and the transverse movement of the translating device, but it may also include means for performing other mechanical functions such, for example, as would be necessary to adjust the translating device to recording or reproducing position. The control means may be of electrical, pneumatic or mechanical form, and/or combinations of these, these means being connected by wiring, tubing or other elongated flexible means to a remote control device usually mounted on the aforesaid hand-piece of the transmitting tube so as to be easily accessible for operation by the operator.

The transmitting tube very desirably swivels relative to the main portion of the machine and is of considerable length to provide a reasonable degree of freedom to the operator. Because of such length it must have a fairly large cross-sectional area in order to provide a sound duct that will efficiently convey the sound waves. Also within or along the sound duct there is usually carried the means for connecting the control device to the control means within the main portion of the machine. These various factors require the transmitting tube to have

such size and weight proportions as to encumber the portability of the machine and to detract from its appearance. It is, therefore, very desirable to have the transmitting tube and the means connecting any remote control device to the operating mechanism, which means may be separate from or carried by the tube, easily detachable from the main portion of the machine.

It is an object of my invention to provide such improved means as will permit a quick and easy detachment of the sound transmitting tube and the control device from the machine.

It is another object to provide improvements for a commercial phonograph which facilitate its portability and enhance its appearance without sacrificing its ease of operation.

It is another object to provide improvements in a commercial phonograph which comprise means for detachably coupling the sound transmitting tube and control device to the main portion of the machine so as to permit a smaller cabinet for such main portion.

It is another object to provide a unitary structure for detachably and swivellingly coupling the sound transmitting tube and remote control device to the main portion of the machine, the coupling being unaffected by the swivelling movement.

It is a still further object to provide means for detachably and swivellingly coupling the sound transmitting tube and remote control device to the main portion of the machine, such means being simple in construction, economical to manufacture, and free from undue strains on any or all of the associated parts.

Other and allied objects will more fully appear from the following description and the appended claims.

In the description of my invention reference is had to the accompanying drawing, of which:

Figure 1 is an elevational view, partially in section, of a portion of a conventional phonograph showing my invention as applied thereto;

Figure 2 is a bottom plan view of the detachable portion of my coupling unit;

Figure 3 is a top plan view of the stationary portion of my coupling unit;

Figure 4 is a bottom view of the detachable portion of my coupling unit in which a bottom part is removed to show the connections made within the unit;

Figure 5 is a cross-sectional detailed view, taken along the line 5—5 of Figure 4, of a portion of my coupling unit;

Figure 6 is an elevational view of a modified

35

form of the coupling unit according to my invention with a portion broken away to show interior parts in cross-section;

Figure 7 is a top plan view, partly in section, 5 of the stationary portion of the modified form of my coupling unit;

Figure 8 is a top plan view of an interior part used in the detachable portion shown in section in Figure 6; and

10 Figure 9 is a sectional view taken along the line 9—9 of Figure 8.

In Figure 1 there is shown in addition to my invention such principal parts of a conventional phonograph as are sufficient to demonstrate the 15 application of my invention thereto. These parts comprise a mandrel 1 rotatably mounted on a base or frame B and carrying removably a cylindrical phonograph record A for rotation in the direction of arrow C. The frame B supports 20 through suitable standards the principal parts of the machine and is ordinarily encased within a suitable cabinet (not shown). A standard 2 secured to or integral with frame B has a bearing 3 for supporting the shaft of mandrel 1. Spaced 25 standards, one of which shown as 5, are also secured to base B and serve to support the longitudinal rods 4 and 4'. Carried slidably upon the rods 4 and 4' is a carriage 6 which has an arm 7 held pivotally thereto by a pivot 8. The arm 7 is normally biased in a leftwise direction by a 30 spring 7' which is disposed about a guide rod 9' secured to carriage 6. The arm 7 carries a feed nut 9 adapted to engage a feed screw 10, this screw being rotatably held in spaced standards, 35 one of which is 5. Suitable gearing (not shown) couples the feed screw 10 to mandrel 1 to effect thereby, as feed nut 9 engages feed screw 10, a transverse movement of carriage 6 with respect to mandrel 1. The engagement of feed nut 9 to feed screw 10 is controlled by a control lever 11 40 which is coupled to arm 7 by means not herein necessary to be described.

The carriage 6 carries a translating device 12 which is adjustable by control lever 11 to a neutral position or to positions for either recording or reproducing purposes. In recording position a stylus 13 is brought into engagement with record A; in reproducing position a stylus 14 engages record A. The translating device 12 is substantially circular in cross-section and is provided with a lug portion 23 extending downwardly from the main portion thereof. It is retained, as by set screws 26, in a suitable recess 23' provided in the foremost part of carriage 6, but projects slightly above the carriage as shown at 22, the projecting portion being circular in cross-section except for the lug portion 23. The translating device 12 is common to the art and need be no more fully described than by the statement 50 that it comprises means, when in recording position, for receiving sound waves and imparting a movement undulating in accordance with those waves to stylus 13, and, when in reproducing position, for creating sound waves in accordance with the undulating movement imparted to stylus 14 by its engagement with a progressive modulated groove on record A. These sound waves are conveyed to, and away from, the translating device 12 by a tubular element 15 55 which comprises a part thereof. Coupled to the tubular element 15 is a sound transmitting tube 16 which carries at its far end a hand-piece 17 adapted to receive sound waves from the vicinity of the speaker's mouth during recording, or alternatively to be used as an earpiece during repro-

ducing. This transmitting tube 16 conveys the sound waves between the hand-piece 17 and translating device 12. It is for reasons already mentioned that it is very desirable to have the transmitting tube 16 detachably coupled to the translating device 12 so that it may be easily removed at the will of the operator. My invention is particularly concerned with means for detachably coupling to the main portion of the machine the sound transmitting tube 16 and, simultaneously therewith, other associated apparatus hereinafter described. It is an added feature of my invention to have this coupling swivelling in a manner to retain all necessary couplings throughout the swivelling movement, and yet to permit ready detachment of all coupled parts.

As hereinbefore mentioned the phonograph comprises an operating mechanism, a principal part of which is a rotative source of power usually comprising an electric motor. The motor is mechanically connected to mandrel 1 to effect a rotation thereof, the connection usually comprising a suitable electromagnetic clutch such, for example, as is illustrated in U. S. Patent No. 1,380,486. The motor and clutch are purely 20 schematically represented in Figure 1 as the mechanism D, this being located in the main portion of the machine and adapted to be controlled readily by the dictator through the provision of a control device 18 mounted on the hand-piece 30 17. This control device 18 is connected by means extending within or along the transmitting tube 16 to mechanism D. The control device 18 comprises a manually operable electric switch of the single pole two-way type. It has a base portion 31 which is integral with the hand-piece 17, and a relatively movable portion 32 secured to the hand-piece as by pivot 31'. This portion 32 is biased upwardly by a suitable spring (not shown) and carries a switch contact point 32' 40 which engages the contact points, 33 and 33', which are held resiliently to the hand-piece 17. In the upward position of the movable portion 32, contact point 32' engages with contact point 33; in the lower position of the movable portion 32 contact point 32' engages contact point 33'. Electrical conductors disposed in cable 19 make connections respectively to the contact points 32', 33 and 33' of the control device 18, and extend along and within the transmitting tube 16 to the coupling unit with which my invention is especially concerned. Within the coupling unit the conductors of cable 19 make connections respectively to the conductors of cable 19', which cable passes over rod 4 and extends outwardly to mechanism D wherein the respective conductors make connection to circuits of the mechanism for controlling its operation by the manipulation of control device 18. Although I illustrate herein a single electrical control means for controlling the mandrel rotation, I intend no unnecessary limitation of my invention to control means which are electrical; neither do I intend my invention to be limited to the mere control of mandrel rotation, or to the employment of a single control means, as I may obviously employ multiple circuits coupling a control device, or devices, manually or otherwise operable, to various mechanisms located within the main portion of the machine. However, for illustrating my invention I show 50 a coupling unit which detachably and swivellingly couples the sound transmitting tube 16 to the translating device 12, and which also detachably couples the control device 18 to mechanism D. A preferred embodiment of my invention as illus- 70 75

trated in Figures 1 to 5, inclusive, is now described in detail.

For illustrating my invention, the coupling unit is shown as comprising two parts: a first part which is held stationary with respect to the translating device 12, and a second part which is swivellingly movable relative to the first part and to which is secured the tube 16. The coupling is preferably so arranged that the parts, after being set in place, form with each other an annular enclosure.

The first part of the coupling comprises the cylindrically shaped ring 21 which fits about the projecting part 22 of the translating device 12, it being suitably cut away at 22' to clear the lug 23. It has an outwardly extending boss 24 in one portion of its periphery. Extending downwardly from this boss is a pin 25 which engages a hole 25' provided in carriage 6. When the ring 21 is placed in position so as to cover the projecting portion 22 of the translating device 12, with the pin 25 engaged in the hole 25', the ring is secure against all except possible upward movement. Within the ring 21 is an annular block 27 made of suitable insulating material and held therein in any suitable manner as, for example, by a pressed fit. Within the block 27 are embedded spaced members or collector rings 28, 29 and 30, made of conductive material and concentrically disposed so as to be insulatedly held from each other. Connected respectively to the collector rings are the conductors comprised in the cable 19, which cable extends outwardly from the ring 21 by way of an aperture 24' provided in the boss 24. The cable 19' is carried in a flexible tube 40 held in the aperture 24' by a set screw 41.

The second part of my coupling unit is swivellingly movable with respect to, and detachable from, the aforementioned stationary part. It comprises an inverted cup member 34 having a central interior tubular element 35, and an exterior tubular element 36 communicating with the tubular element 35, the element 36 extending angularly away from the top 37 of the inverted cup member 34. The interior tubular element 35 fits telescopically over the tubular element 15 of the translating device 12, and acts as a bearing therewith for the swivelling movement of cup member 34. The interior tubular element 35 thus forms with the tubular element 15 a sound duct for sound transmission therebetween. Attached to the exterior tubular element 36, as by set screw 38, is the transmitting tube 16 having at its outer end the hand-piece 17. Thus a continuous sound duct is formed between the hand-piece 17 and the translating device 12.

The member 34 is permitted to swivel with respect to the tubular element 15 of the translating device 12. It may be retained thereto by means of a single pin 20 secured to the member 34 and adapted to engage a segmental groove 20' on the tubular element 15. When the member 34 is in its proper mechanical relationship with the tubular element 15 its outside wall 39 rests slidably upon the rim of ring 21, thereby retaining ring 21 against upward movement. Impingement of the inner end portion of pin 20 upon the extremities of the segmental groove 20' appropriately limits the arc through which the movable part, or member 34, of the coupling unit swivels. The pin 20 is held slidably within a sleeve member 42 which has a reduced diameter over its inner end portion 42', which portion fits tightly into an aperture 43 of the interior tubular element 35 of member 34. The pin 20 extends slidably through

a cylindrical cup member 44 which is threaded through the outside wall 39 of member 34 until it engages the end of the enlarged diameter portion 42'' of sleeve 42. A collar 45 held to pin 20 limits its inward movement, by impingement against the outer end of the reduced diameter portion 42' of sleeve 42. A spring 46 disposed about pin 20 between collar 45 and member 44 biases the pin 20 inwardly. The pin 20 may be moved outwardly, as would be necessary in the assembly or disassembly of the coupling unit, by manually operable means comprising, for example, a knob 41 secured to its outer end.

Within the inverted cup member 34, between its interior tubular element 35 and outside wall 39, is disposed an annular block 48 made of suitable insulating material. Secured to this block 48, as by suitable screws, are springs 28', 29' and 30', which carry at their outer ends pin members 28'', 29'' and 30''. The conductors of cable 19, already described, extend through the aperture 48' of block 48 and connect respectively to the springs 28', 29' and 30'. The pin members 28'', 29'' and 30'' are guided by extending through suitable apertures of a ring-shaped insulating plate 49 held to block 48, as by screws 50, and are respectively adapted to slidably engage collector rings 28, 29 and 30 to make electrical connections therewith. These electrical connections couple the respective conductors of cable 19 to the respective conductors of cable 19'. This coupling is disposed around and along the sound duct formed by the telescoping of tubular element 15 with the interior tubular element 35. It is effected with the attachment of the removable cup member 34, as already described, and is retained throughout the swivelling movement of this member. By this arrangement it is obvious that control device 18 is coupled to mechanism D in response to, or as an incident of, coupling transmitting tube 16 to translating device 12; likewise, control device 18 is detached from mechanism D in response to, or as an incident of, detaching transmitting tube 16 from translating device 12.

A modified form of my invention as illustrated in Figures 6 to 9 inclusive is now described. In this modified form there is employed the ring 21 and inverted cup member 34 of my preferred form. The ring 21 again comprises the stationary part of the coupling unit and carries an annular block 51 made of suitable insulating material held therein in a suitable manner as by a pressed fit. The block 51 carries mutually similar spaced members or collector rings 52, 53 and 54 coaxially disposed to the ring 21 and insulatedly held from one another. Connected respectively to the collector rings 52, 53 and 54 are the conductors comprised in the cable 19, which cable extends outwardly through the aperture 24' of boss 24 as has been described.

The second part of this modified form is again swivellingly movable and detachable with respect to the tubular element 15 and the aforementioned stationary parts. It comprises the inverted cup member 34 into which, between the tubular element 15 and the outside wall 39, is disposed a tubular member 55 made of suitable insulating material. This tubular member 55 has a flanged portion 55' near its upper end. Extending radially through the portion 55' is an aperture 56 adapted to receive a screw 57 threaded through the outside wall 39 of cup member 34 so as to retain the tubular member 55 in its proper mechanical relation to member 34. The tubular

member 55 has longitudinal slots 58, 59 and 60 from its flanged end 55' almost to the other end 55'', these slots extending outwardly partially through the flanged portion 55'. The member 55 has other longitudinal slots 58', 59' and 60' cut respectively in the outside of the flanged portion 55' in radial alignment to the slots 58, 59 and 60. These slots are disposed in equal space relationship about the periphery of the tubular member 55. Secured to the tubular member 55, as by screws (not shown), within the smaller slots 58', 59' and 60' are the respective conductive springs 61, 62 and 63. These springs extend into the slots 58, 59 and 60, and downwardly therethrough, so as to slidably engage the respective collector rings 52, 53 and 54 for making electrical connection thereto. These connections are made with the attachment of the removable cup member 34 and are maintained throughout the swivelling movement 20 of this member. Connected respectively to the springs 61, 62 and 63 are electrical conductors. These conductors are comprised in the cable 19 and extend through the aperture 48' and onwardly into the transmitting tube to make connection to the control device 18, as has been described. Thus, in response to the coupling of the transmitting tube 16 to the translating device 12, control device 18 is coupled to mechanism D.

The screw 57 which retains the tubular member 55 in its proper position comprises the body of a plunger construction for retaining the cup member 34 to the tubular element 15. This screw 57 has a hollow portion extending from its inward end in which is carried a ball 57' biased outwardly by means of a spring 57'' disposed within the hollow portion. The ball, which is restricted in its outward movement by a peening of the inner end of the screw 57, engages the annular groove 28'' of the tubular element 15 to retain 40 swivellingly the cup member 34 to the tubular element 15 of the translating device 12. Although the engagement of the ball 57' with the groove 28'' serves to retain the removable portion of my coupling unit sufficiently well against possible detachment in normal use, it is obvious that the removable portion is detachable by the mere exertion of an upward force thereon. It is also to be understood that when the cup member 34 is retained in its proper mechanical relationship to the tubular element 15, the wall 39 of member 34 rests slidably upon the rim of the ring 21, thereby preventing it against possible upward movement.

I have herein disclosed my invention in terms of two specific embodiments, but it will be understood that these embodiments are merely illustrative of my invention and not limitative thereof. Although the forms of mechanism shown and described serve admirably to fulfill the objects 60 primarily stated, the same may be fulfilled in various other forms without departing from the spirit of my invention. It is of course obvious that there may be many modifications in the construction and arrangement of the embodiments 65 herein shown. I have, for example, illustrated my invention as comprising a detachable portion carrying spring contacting members, and a stationary portion carrying collector rings; but I may reverse this order so that the detachable 70 portion carries the collector rings, and the stationary portion carries the spring contacting members. Such modifications and other forms will not necessarily constitute a departure from the true scope of my invention, which I undertake to express in the following claims.

I claim:

1. In a phonograph comprising an operating mechanism, a sound translating device, a sound transmitting tube, and a control device mounted on said tube for controlling said mechanism: the combination of means for acoustically coupling said tube to said translating device; means comprising two connectable portions for coupling said control device with said operating mechanism; and means, joining said two connectable portions with said tube and translating device respectively, for effecting the coupling of said control device with said operating mechanism as said tube is acoustically coupled to said translating device.

2. In a phonograph comprising an operating mechanism, a sound translating device, a sound transmitting tube communicating with said translating device and having a junction point therebetween, and a control device mounted on said tube and connected with said operating mechanism for controlling the mechanism: the combination of means for detaching said transmitting tube from said translating device at said junction point; means comprising two portions separable from each other for disconnecting said control device from said operating mechanism; and means, joining said two separable portions with said tube and translating respectively, for effecting the disconnection of said control device from said operating mechanism as said transmitting tube is detached from said translating device.

3. In a phonograph comprising an operating mechanism, a sound translating device, a sound transmitting tube, and a control device mounted on said tube for controlling said mechanism: the combination of two connectable and relatively swivellable members for acoustically coupling said tube with said translating device; means comprising two connectable portions for coupling said control device with said operating mechanism; and means, joining said two portions with said two members respectively, for rendering said control device coupled with said operating mechanism throughout the relative swivelling movement of said two members when said transmitting tube is coupled with said translating device.

4. In a phonograph comprising an operating mechanism, a sound translating device, a sound transmitting tube, and a control device mounted on said tube for controlling said mechanism: the combination of two connectable and relatively swivellable members for acoustically coupling said tube with said translating device; means comprising two connectable portions for coupling said control device with said operating mechanism; and means, joining said two portions with said two members respectively, for causing the disconnection of said control device from said operating mechanism as said two members are separated for detaching said tube from said translating device.

5. In a phonograph comprising an operating mechanism, a sound translating device, a sound transmitting tube, and a control device mounted on said tube for controlling said mechanism: the combination of two connectable and relatively swivellable members for acoustically coupling said tube with said translating device; and means comprising two connectable portions carried by said two members respectively, for rendering said control device coupled with said operating mechanism throughout the relative swivelling movement of said two members when said two mem- 75

- bers are connected with one another for coupling said tube with said translating device.
6. In a phonograph comprising an operating mechanism, a sound translating device, a sound transmitting tube, and a control device mounted on said tube for controlling said mechanism: the combination of means for acoustically coupling said tube to said translating device; and means comprising two connectable portions carried by and disposed concentrically with said tube and translating device respectively, for coupling said control device with said operating mechanism incidental to the act of coupling said transmitting tube with said translating device.
15. 7. In a phonograph comprising an operating mechanism, a sound translating device, a sound transmitting tube communicating with said translating device and having a junction point therebetween, and a control device mounted on said tube and connected with said operating mechanism for controlling the mechanism: the combination of means for detaching said transmitting tube from said translating device at said junction point; and means comprising two separable portions disposed at said junction point and carried by said tube and translating device respectively, for disconnecting said control device from said operating mechanism incidental to the act of detaching said transmitting tube from said translating device.
30. 8. In a phonograph comprising an operating mechanism, a sound translating device, a sound transmitting tube, and a control device mounted on said tube for controlling said mechanism: the combination of means coupling said tube with said translating device and forming a sound duct therebetween, portions of said means forming with said translating device an annular enclosure surrounding said duct; and connectable means disposed in said enclosure for coupling said control device with said operating mechanism as an incident of the coupling of said tube with said translating device.
9. In a phonograph comprising an operating mechanism, a sound translating device, a sound transmitting tube, and a control device mounted on said tube for controlling said mechanism: the combination of means for acoustically coupling said tube with said translating device, comprising a part in fixed relationship to said translating device and a relatively swivellable part, said second part having an interior tubular element engaging said translating device; and means comprising two connectable portions disposed in fixed relation to said first and second parts respectively, for swivellingly coupling said control device with said operating mechanism when said transmitting tube is acoustically coupled to said translating device.
60. 10. In a phonograph comprising an operating mechanism adapted to be electrically controlled, a sound translating device, a sound transmitting tube, and a switch device mounted on said tube for controlling said mechanism: The combination of means coupling said tube to said translating device and forming a sound duct therebetween; a plurality of spaced conductive members surrounding said sound duct and connected with said operating mechanism; and a plurality of resiliently held brushes connected with said switch device and adapted to engage said conductive members respectively, for coupling said switch device with said operating mechanism while said transmitting tube is coupled with said translating device.
11. In a phonograph comprising an operating mechanism, a sound translating device, a sound transmitting tube, and a switch device mounted on said tube for controlling said mechanism: the combination of means swivellingly coupling said tube to said translating device and forming a sound duct therebetween; and means for coupling said switch device with said mechanism as an incident of the coupling of said tube to said translating device, comprising collector rings concentrically disposed about said sound duct and resiliently held brushes adapted to slidably engage said collector rings for continuous electrical connection therewith throughout the relative swivelling movement of said tube with said translating device.
15. 12. In a phonograph comprising an operating mechanism, a sound translating device, a sound transmitting tube, and a switch device mounted on said tube for controlling said mechanism: the combination of means swivellingly coupling said tube to said translating device and forming a sound duct therebetween; a plurality of collector rings coaxially disposed about said sound duct and connected with said operating mechanism; and a plurality of resiliently held brushes connected with said switch device and adapted to slidably engage said collector rings respectively for coupling said switch device with said operating mechanism while said transmitting tube is coupled to said translating device.
20. 13. In a phonograph comprising an operating mechanism, a sound translating device, a sound transmitting tube, and a switch device mounted on said tube for controlling said mechanism: the combination of means for swivellingly and acoustically coupling said tube to said translating device; means for limiting the degree of said swivelling movement; and connectable means for electrically coupling said switch device with said operating mechanism as an incident of the coupling of said transmitting tube to said translating device, comprising spaced conductive members and resiliently held brushes slidably contacting said members respectively for electrical connection therewith throughout the range of said swivelling movement.
25. 14. In a phonograph comprising an operating mechanism, a sound translating device, a sound transmitting tube, and a control device mounted on said tube for controlling said mechanism: the combination of a tubular element on said translating device communicating therewith; a coupling member carried at one end of said transmitting tube for telescopically engaging said tubular element; and means, comprising two connectable portions respectively carried by said translating device and said coupling member, for coupling said control device with said operating mechanism incidental to the act of telescopically engaging said coupling member with said tubular element.
30. 15. In a phonograph comprising an operating mechanism, a sound translating device, a sound transmitting tube, and a control device mounted on said tube for controlling said mechanism: the combination of a tubular element secured to said translating device and forming a sound duct thereto; a coupling member secured to said tube having a tubular element adapted to telescopically engage said first tubular element; one of said tubular elements being provided with a transverse groove; securing means on the other of said tubular elements biased to engage said groove for retaining said coupling member swiv-

ellingly to said translating device; and means, comprising two connectable portions respectively carried by said coupling member and said translating device, adapted to couple said control device with operating mechanism as the respective tubular elements of said translating device and coupling member are brought into telescopic engagement with one another.

16. In a phonograph comprising an operating mechanism, a sound translating device, a sound transmitting tube, and a control device mounted on said tube for controlling said mechanism: the combination of a tubular element secured to said translating device and forming a sound duct thereto, said element being provided with a trans-

verse groove on the outer surface thereof; a coupling member secured to said tube having a tubular portion adapted to telescopically engage said tubular element; securing means on said coupling member biased inwardly to engage said groove for retaining said member swivellingly to said tubular element; and means, comprising two connectable portions respectively carried by said coupling member and said translating device, adapted to couple said control device with said operating mechanism as the tubular portion of said coupling member is brought into telescopic engagement with the tubular element of said translating device.

SAM G. LANGLEY. 15
